UNITED STATES PATENT OFFICE.

JULIUS DICKERT, OF CHICAGO, ILLINOIS.

PROCESS OF TREATING AND PRODUCING CORRECTED HALFTONE PLATES OR METALLIC PRINTING PLATES.

Application filed July 24, 1922. Serial No. 576,996.

To all whom it may concern:

Be it known that I, JULIUS DICKERT, a citizen of the United States, residing in Chicago, in the county of Cook and State of Illinois, have invented certain new and useful Improvements in Processes of Treating and Producing Corrected Halftone Plates or Metallic Printing Plates, of which the following is a specification.

10 This invention relates to an improved process of treating and producing corrected half-tones, electrotype plates, or other metallic printing plates, and to half-tones, electrotype plates or other metallic printing plates made in accordance with my improved process.

It relates particularly to half-tone plates, electrotype plates or other metallic printing plates made in accordance with my improved process and having what is commonly termed and known as the "make-ready," in the metallic printing plate when completed and ready for use.

The principal object of this invention is to provide a simple, economical, and efficient process of treating and producing corrected half-tone plates, electrotype plates, or metallic printing plates, and including the process of so forming such metallic printing plates that the "make-ready" will be embodied in the printing plate or completed in the operation of completing such printing plate, so that a further operation to complete a "make-ready" will be, so far as possible, unnecessary, and may, in many instances, be entirely dispensed with.

Other and further objects of the invention will appear from the following description and claims, and from the accompanying drawings, which are made a part hereof.

The invention consists in the improved process of treating and producing corrected half-tones, electrotype plates, or metallic printing plates herein described and claimed, and in half-tones, electrotype plates or other metallic printing plates made in accordance with my improved process.

In the accompanying drawings:

Figure 1 is a plan in view of a photo-

surface, in accordance with my improved process and invention;

Fig. 2 is a similar view of a transparent sheet or proof-sheet made from the original photo-engraving or image shown in Fig. 1;

Fig. 3 is a similar view of a completed metallic make-ready overlay plate or sheet made in accordance with my improved process and having a pictorial image thereon corresponding with the picture, image or design on the original photo-engraving or picture shown in Fig. 1, but with the highlights or high-light surfaces in the make-ready overlay plate corresponding with shadow-tones in the original photo-engraving or picture, and vice versa;

Fig. 4 is a similar view of a half-tone plate, electrotype, or metallic printing plate, to be operated upon and impressed or made ready and completed in accordance with my improved process, and by means of the metallic make-ready overlay plate or sheet shown in Fig. 3;

Fig. 5 is a similar view showing a metallic make-ready plate, made in accordance with my process, but by making a proof in ink from the original photo-engraving directly upon the sensitized coated surface of the metallic overlay plate;

Fig. 6 is a view in side elevation showing the transparent sheet of Fig. 2 in contact with the inked printing surface of the original photo-engraving, shown in Fig. 1, in the operation of taking a proof in ink on said proof-sheet, or transparent sheet;

Fig. 7 is a similar view in side elevation, showing the transparent sheet of Fig. 2 having the image in ink thereon on one side thereof, but with the other side in contact with the sensitized film-coated surface of the metallic make-ready overlay plate or sheet shown in Fig. 3, in the process of printing the image on the sensitized surface or coating of said make-ready overlay plate by means of rays of light passing through the transparent sheet;

Fig. 8 is a similar view in side elevation, showing the metallic make-ready overlay plate or sheet of Fig. 3 in contact with the printing surface of the half-tone or electro-

type plate shown in Fig. 4, as it would be in the process of applying pressure and impressing or making ready said half-tone plate, metallic printing plate or electrotype

plate, by passing the metallic overlay plate into or against the half-tone plate, in accordance with my improved process;

Fig. 9 is a similar view in side elevation, showing a metallic make-ready overlay plate, such as that shown in Fig. 3 or Fig. 5 in contact with the printing surface of the half-tone or electrotype plate of Fig. 4, and with a mould identical with the metallic overlay plate, but with the position of the image reversed and with the high-lights in the mould corresponding with the shadow-tones in the metallic overlay plate, and vice-versa, in contact with the back of the half-tone or electrotype plate, shell or printing plate, in the process of applying pressure and impressing the make-ready overlay plate or sheet, or its image upon the half-tone or metallic printing plate;

Fig. 10 is an enlarged detail view in section of a metallic make-ready overlay plate or sheet, such as that shown in Fig. 3 and in Fig. 5, showing a plurality of gradations, representing high-lights, middle-tones, and shadow-tones, respectively, in the etched surface of the metallic make-ready overlay plate;

Fig. 11 is an enlarged detail view in section, showing the metallic make-ready overlay plate in finished form and in contact with the printing surface of the half-tone, electrotype plate or metallic printing plate, and with the gradations representing the high-lights, middle-tones and shadow-tones indicated diagrammatically, or on a greatly enlarged scale; and

Fig. 12 is a view in side elevation showing the original photo-engraving, with its inked face in direct contact with a make-ready plate and in position to print an image in ink directly upon the latter.

In practicing my improved process, and treating and producing a corrected half-tone plate, electrotype plate, or metallic printing plate or plates in accordance with my process and invention, I provide an original photo-engraving 1, or similar picture, image or design made in any desired ordinary and well known manner, from which such half-tone plate, electrotype plate, or metallic printing plate or plates are to be made.

I also provide a metallic make-ready overlay plate or sheet 3, formed of zinc, brass, copper, aluminum, or other suitable metal in plate or sheet form. This metallic make-ready overlay plate is covered with a sensitized solution, coating of film 3' on one side thereof, said coating being made of suitable material which is sensitive to and adapted to be hardened or made more impervious to water by the action of rays of light, and may be in the form of a sensitized solution containing bichromate of ammonia, albumen, or whites of eggs, and water, all dissolved and intermixed in the ordinary

manner familiar to those skilled in the art of photo-engraving.

I also provide an electrotype plate, half-tone plate, or metallic printing plate 4 which may be made from the original photo-⁷⁰ engraving or subject 1, in any desired ordinary and well known or suitable manner, and is adapted to be completed and made ready and perfected by and in accordance with my improved process,⁷⁵ whereby such printing plate will have what is commonly known as a "make-ready" embodied in the metallic printing plate and its printing surface, when the plate is completed.

In practicing my improved process and invention in the manner which will be herein first described, I also provide a thin sheet 2 of suitable flexible sheet material or printing paper, such, for example, as tissue paper, onion skin paper, waxed paper, or other sheet material such as celluloid, or other suitable material, which is already transparent or adapted to be made transparent. The sheet 2, when made of paper or similar material, may be made transparent, either before or after printing thereon, by saturating the same with vaseline, lard, ordinary machine oil, or other suitable material.

I then ink the printing face of the original photo-engraving or subject 1 with a suitable coating of ink, which may be applied in the manner ordinarily employed in making a proof or print from a photo-engraving or printing plate.

I then, by preference, dust the sheet or inked image in the sheet 2 with a resinous powder, or powdered bronze or asphaltum powder, or what is commonly known in the art as dragon's blood powder.

I then make a proof, print, or imprint from the inked printing surface of the photo-engraving or subject 1 upon either the thin proof sheet or transfer sheet 2, to be afterward transferred to or printed upon the sensitized coated surface 3' of the metallic make-ready overlay plate or sheet 3; or else, I make such proof from the inked printing surface of the original photo-engraving or subject 1 directly upon said sensitized or coated surface 3' of the metallic make-ready overlay plate, or sheet 3.

In practicing my process in the manner which will be herein first described, in which the thin sheet 2, or sheet of transparent material is employed, I first take the proof on said sheet 2 from the inked printing surface of the original photo-engraving 1, as already suggested, and then lay the thin sheet 2, or transparent sheet, upon and in contact with the sensitized coated surface 3' of the metallic make-ready overlay plate or sheet 3, but, by preference, with the inked side of the sheet 2 out of contact with said surface of the metallic plate

3. And the image or outline on the sheet 2 is thus printed or reproduced directly on the sensitized surface of the metallic make-ready overlay plate or sheet 3 by the action of rays of light passing through the transparent proof sheet 2.

In printing through the transparent sheet 2, or from said sheet onto the sensitized coating on the make-ready overlay plate 3 by means of rays of light, it is only necessary to expose said plate and coated sheet to the action of the rays of light from an electric light, such as is commonly used in the art of photo-engraving, for approximately three minutes, or to direct rays from the sun, or other source of light for a sufficient period of time, thus causing the rays of light to effect the sensitized solution or coating 3' on all parts of the coated surface of the make-ready overlay plate, except the part or parts covered by the image and shielded and protected from the action of the rays of light by the ink or inked surface of the image.

Having printed the image upon the sensitized coating of the make-ready overlay plate 3, by subjecting the sensitized coating to the action of rays of light in the manner above described, the sheet 2 is removed, and the entire surface of the sensitized coating of the metallic make-ready overlay plate or sheet 3 is covered with a coating of ink, the ink being applied thereto by means of an inked roller, and the sensitized ink-covered coating or coated surface of the make-ready overlay plate 2 is then developed by laying the plate in water, preferably running water; and, to facilitate the development, the plate may be rubbed with cotton, or similar material, while under and subjected to the action of the water. This develops or brings out the image in the form of an ink-covered replica, or reproduction, of the image of the original photo-engraving on the sensitized coating of the metallic make-ready overlay plate 3.

This washing of the plate with water removes the relatively soft ink-protected portions of the sensitized coating wherever the coating has not been hardened by the action of the rays of light, leaving the metallic surfaces of the plate exposed, and leaves on the plate the portions of relatively hard sensitized coating, which have been exposed to the rays of light during the printing operation above described.

The replica or image on the sensitized film or coating in the make-ready overlay plate, however, differs from the original image on the photo-engraving in respect to the relations of the high-lights, middle tones and shadow-tones. The high-lights or deepest depressions of gradations in the image on the make-ready overlay plate 3,

when the plate is finally etched and completed, will correspond with the shadow-tones or heaviest and most prominent surfaces, dots or gradations of the original photo-engraving, and on the finished half-tone plate or electrotype plate, and vice-versa.

The plate is now dried and then dusted with a resinous powder, commonly known as dragon's blood powder, which adheres to the inked surface of the sensitized coating, particularly when heated, but does not adhere to the exposed clean metallic surface from which both ink and sensitized coating have been removed.

The plate with the coating of ink and powder thereon is then heated by suitable heating means, which may be of any desired ordinary and well known form, thereby heating and melting, or baking the resinous powder, or dragon's blood powder, and making it adhere to the inked surface so as to form an acid resisting coating over the sensitized solution or coating, wherever the latter remains upon the metallic plate.

The object of heating the plate now covered with ink and dragon's blood powder is that it hardens the ink and makes it resist the acid to a greater extent than it otherwise would. The plate is now ready to be etched.

The back of the metallic make-ready overlay plate is now painted with an acid resisting varnish or paint, such as is common and well known in the art of photo-engraving, leaving the exposed metallic surface, wherever it remains uncovered by either ink or sensitized coating, in condition to be acted upon by acid, or etched.

An acid bath is provided consisting of a solution containing water and nitric acid in suitable proportions, for example, in substantially the proportions of one part nitric acid to five parts of water, but which proportions may be varied as conditions may require. Such an acid bath suitable for this purpose is common and well known to those skilled in the art of photo-engraving, and therefore need not be further described herewith.

For example, a nitric acid solution is used for etching zinc make-ready plates, and per chloride of iron for etching plates or sheets of copper or of brass.

The plate, thus covered with ink and powdered wherever the ink and powder will adhere to the coated surface, but with the metal surface exposed in a greater or less degree, particularly where the ink and powder have not adhered to the surface, is put into the acid bath, above mentioned, for etching, and rocked for about five minutes, or until the high-light surfaces or gradations of the metallic make-ready plate have sufficient depth, and until the exposed metal

has been etched away sufficiently to form the required depressions and elevations or gradations in the metallic surface. These gradations correspond with or form what may be termed the high-lights, middle-tones and shadow-tones, respectively, in the make-ready overlay plate or sheet. The bottom gradations, or high-lights, in metal make-ready overlay plate, which constitute the deepest depressions in the surface of the plate, are thus thoroughly cleaned and etched to the desired depth. Wherever the zinc or metallic surface of the plate is exposed and not covered with ink or inked sensitized coating, throughout any portion of the design the metal is eaten away or etched away by the acid to the required depth, and the design or surface of the plate, wherever it is covered with acid resisting ink and powder, is, of course left with the ink covered metallic surface higher than the part that has been etched away.

I then wash off all ink from the surface of the plate with benzine, turpentine, or other suitable liquid solution or material.

After the ink has been thus washed off the plate, the sensitized solution still remains on all parts of the plate, except the part that has been etched by the action of the acid; but the part of the surface of the plate and of the image which has not been etched is still covered with the coating of sensitized solution even after the ink has been removed. In fact, the coating of sensitized solution which now remains on the plate may be said to be only on that part of the plate where the image or portions of the image remains as a raised surface portion of the plate.

A weak solution of muriatic acid,—for example, a solution consisting of or containing one part of muriatic acid to five parts of water—is then applied upon the middle-tone surfaces, dots, or middle-tone gradations, by means of a small brush. This application of muriatic acid removes the sensitized solution from the middle-tone surfaces or gradations, and leaves the metal surface of the middle-tone and high-light gradations exposed and clean.

The plate is then again immersed in a nitric acid solution, such as the nitric acid bath, already described, and given a slight etch, while the sensitized solution is still covering and protecting and holding up the shadow-tone surfaces or gradations, and also what is commonly called the dead metal surfaces. This etch is to bring down the middle-tone surfaces or gradations, and the high-light surfaces or gradations, but without effecting the shadow-tone surfaces or gradations.

The plate is then again washed with water, and is then again immersed in a weak

solution of muriatic acid to remove all of the remaining sensitized solution from the surface of the plate.

The plate is then again washed with water and again put into the nitric acid bath and given a slight etch to round off the sharp angles or corners and cause the high-light, middle-tone and shadow-tone surfaces or gradations to merge to a sufficient extent to prevent or remove any undesirable sharpness or prominence of the margins of the various gradations. The nitric acid is then washed off; and the varnish is removed from the back by the application of turpentine, benzine, or other suitable material.

The metallic overlay or make-ready plate is then laid in contact with the printing side of the half-tone plate, electrotype plate, or metallic printing plate, said printing plate being supported upon a bed or table, or a wall of a suitable mold or other suitable support. And pressure is applied to the back or exposed side of the metal make-ready plate, or to both the make-ready plate and half-tone or electrotype plate. The printing plate and make-ready plate or overlay are thus pressed together with such force as to cause an impression of the face of the metallic make-ready overlay plate to be impressed upon or reproduced in and upon the printing side of the electrotype plate.

This pressure may be applied in any desired suitable or ordinary manner, by means of hydraulic pressure, or any suitable means for applying pressure known to the art to which this invention relates.

A metallic mold formed of lead or other suitable material 5', of identical construction with the make-ready overlay plate, already described, but with the high-lights and shadow-tones or depressions and elevations reversed with respect to those of the overlay plate, above described, and with the position of the image corresponding with that of the original photo-engraving and original electrotype plate, is laid, when desired, in contact with the back of the electrotype plate, while the metallic make-ready plate is in contact with the printing face of the electrotype plate, during the operation of applying pressure to impress the make-ready plate upon the printing face of the electrotype plate.

Such a mold may be made by making an impression of the overlay plate 3 in the face of a sheet or plate of lead, or other suitable material; or it can be made in a similar manner to that in which the metallic make-ready overlay plate is made by etching a plate to form the mold 5'. In making such a mold by etching, a sheet of suitable flexible material identical with the proof sheet 2 may be provided and a proof made thereon direct from the printing face of the

original photo-engraving, and then the inked surface of the proof sheet is laid directly upon the surface of a metallic plate 5', and then removed, leaving an inked proof on the coated surface. And then the etching of the mold plate 5' is completed in substantially the same manner as the make-ready overlay plate 3, already described, but leaving high-light surfaces and shadow-tone 10 surfaces in reversed relation to those of the metallic make-ready sheet.

The original photo-engraving and the transparent proof sheet, as well as the overlay plate, half-tone plate, or electrotype 15 printing plate, and mold, are all provided with a series of suitable register marks 6, whereby said plates and sheet may be accurately positioned with respect to each other during the operation in which any two or 20 more of said members are laid together in the practice of my improved process and invention.

And to further insure the proper registration of the make-ready plate and metallic 25 printing plate, holes may be drilled through both and pins inserted through the holes. And the holes and pins may also extend through the molds 5' when such a mold is used.

What I have termed the high-lights, high-light dots, surfaces or gradations, the same being the deepest depressions, or gradations 30 in the face of the metallic make-ready overlay plate are indicated by the reference numeral 3'; the middle-tones, middle-tone dots, surfaces, or depressions in said make-ready plate being indicated by the reference numeral 7; and the shadow-tones, shadow-tone 35 dots, surfaces or depressions in said make-ready plate, the same being the highest and most prominent gradation or gradations in said make-ready plate, being indicated by the reference numeral 8. And all of said high-light, middle-tone, and shadow-tone 40 dots, surfaces or gradations are shown diagrammatically in greatly enlarged magnified form, in Fig. 10, and also in Fig. 11, and in less exaggerated form in Figures 1 to 5, inclusive. In said Figures 1, 2, 4 and 5, 45 inclusive, the high-light tones, surfaces or gradations 6, are indicated in the image of the moon, the middle-tones and middle-tone gradation or gradations 7, by the surface of the water and the sky, and the shadow-tones, shadow-tone dots, or gradations 8, by the image of the hills and tree. But in 50 Fig. 3 the high-lights or high-light gradations and the shadow-tones or shadow-tone gradations are reversed, as compared with the other Figures 1, 2, 4, 5, as already described, in the sense that the hills represent the high-lights, or high-light gradation, and the moon represents the shadow-tone surface 55 or gradation in said metallic make-ready overlay plate. It should be noted that the

make-ready overlay plate 3 is shown in Fig. 3 in its completed form, while in Fig. 5 the metallic make-ready overlay plate 9 is shown as it would appear immediately upon printing a proof in ink directly upon the sensitized surface of said plate 9 from the inked surface of the original photo-engraving shown in Fig. 1, which may be done whenever it is found more desirable; or in other words, when the use of a transparent proof sheet is to be dispensed with.

Having described my improved process and invention as practiced in cases where a transparent proof sheet, such as the sheet 2, is used, I will now describe the manner 80 of practicing said process without the use of such transparent proof sheet or transfer sheet, as follows:

A suitable polished plate or sheet of zinc or other suitable material from which 85 a metallic make-ready plate or overlay plate, or sheet 3 is to be made, is provided, as shown in Figs. 5 and 12, in which said plate or sheet is indicated by the reference numeral 9.

The make-ready overlay plate or metallic 90 sheet 9 is provided with a sensitized coating identical with the coating 3', already described. Instead of using a transparent transfer sheet or proof sheet 2, the original 95 photo-engraving 1 is provided with a coating of ink applied to its printing surface by means of an inked roller in the manner already described, and the inked image is printed in ink directly from the face of 100 the original image or photo-engraving 1 upon the sensitized coating 3', on the metallic overlay plate or sheet 9, using the usual registering marks in order to insure the proper 105 positioning of the plates relatively to each other.

The metallic make-ready overlay plate 9 with its sensitized coating inked, as shown 110 in Fig. 3, is then printed by being placed in an exposed position so as to receive the rays of light, from the sun, or other suitable source of light, for a suitable length of time, for example, for about three minutes, as already described. Before exposing the 115 coated plate to the rays of light, however, the inked surface is dusted with dragon's blood powder or resinous powder, or similar material adapted to render the inked surface more opaque, or more impervious to the action of the rays of light.

The ink, inked image or outline on the 120 sensitized coated surface of the make-ready overlay plate is then cleaned off with turpentine, benzine, or other suitable material, leaving the sensitized solution still on all parts of the coated side or surface of the plate. It is then only necessary to proceed in the same manner already described, to the completion of the metallic make-ready 125 overlay plate, and of the half-tone plate,

electrotype plate, or metallic printing plate, which, when completed, will embody a complete "make-ready" in the body and printing surface of such half-tone plate, electrotype plate, or metallic printing plate.

It will be readily understood by those skilled in the art of photo-engraving that half-tone plates, electrotype plates, or other metallic printing plates made, and provided with a "make-ready" in accordance with my improved process and invention, as herein described, are adapted for use either in one-color work, two-color work, three-color work, or four-color work, or in work requiring any desired color or combination of colors, or any desired number of printing plates to be used in the ordinary manner in doing color work, or multi-color printing. And it will be readily understood that each half-tone plate, or metallic printing plate, to be used for such color-work, may be perfected or made ready in the manner hereinabove described.

And while I have referred to high-lights, middle-tones, and shadow tones, and have refrained from referring to the various colors, or tones produced or employed in color-printing or multi-color work, it will be readily understood by those skilled in the art of photo-engraving that any desired color or tone may be employed upon any one or more of any desired number of half-tone plates, electrotype plates, or metallic printing plates, to be employed in color-printing, or to be used in printing from one or any desired number of such printing plates successively upon the same surface, page, or sheet, or other object, in the process or art of color-printing.

For example: For four-color printing, yellow, red, blue, and black may be used, with a different printing plate for each color. For three-color work, yellow, red, and blue may be employed, with a separate and distinct printing plate made in accordance with my improved process and invention, for each color, respectively.

And for two-color work blue and orange, or black and orange, or any desired colors or tones, or different variations of colors, may be employed.

The herein described process is capable of being employed for making either flat or curved half-tone plates, electrotype plates, or other metallic printing plates; and the plates which have been perfected or provided with a make-ready embodied in the body and surface of the plate may be curved in any desired ordinary and well known or suitable manner, for example, by passing the same between suitable plate-bending rolls while heated to a suitable temperature for bending, and after the plate has been impressed or made ready in accordance with

my improved process, as above described. 65

I claim:

1. A process of treating half-tone plates, electrotype plates and other metallic printing plates which comprises etching an image on the surface of a make-ready sheet corresponding with the image on the printing side of a metallic printing plate to be made ready, then forcing the etched surface of the make-ready sheet against the printing surface of such metallic printing plate by 70 means of pressure, thereby impressing upon the printing surface of the metallic printing plate the image which is etched upon the surface of the make-ready sheet.

2. A process of treating half-tone plates, electrotype plates and other metallic printing plates which comprises etching an image on the surface of a metallic make-ready sheet corresponding with the image on the printing side of a metallic printing plate to 75 be made ready, but with the high-light surfaces on the make-ready sheet corresponding with the position of the shadow-tone surfaces on the metallic printing plate, and the shadow-tone surfaces on the make-ready sheet corresponding with the high-light surfaces on the metallic printing plate, then laying the etched surface of the make-ready sheet in contact with the printing side of the metallic printing plate to be made ready, 80 then forcing the etched surface of the metallic make-ready sheet against the printing surface of the metallic printing plate, thereby impressing upon the printing surface of the metallic printing plate the image 85 which is etched on the surface of the make-ready sheet.

3. The process of treating half-tone plates, electrotype plates and other metallic printing plates which comprises etching an image 90 on the surface of a metallic make-ready overlay sheet, said image corresponding with an image on the printing side of a metallic printing plate to be made ready, but having the high-light surfaces of the etched metallic make-ready overlay sheet in contact with the corresponding shadow-tone surfaces of the metallic printing plate and having the shadow-tone surfaces of the make-ready overlay plate in contact with the high-light 95 surfaces of the metallic printing plate, and then forcing the etched surface of the metallic make-ready sheet against the printing surface of the metallic printing plate by means 100 of pressure, thereby impressing upon the high-light surfaces on the printing plate the impression of the corresponding surface portions of the image etched upon the metallic make-ready overlay plate.

4. The process of treating half-tone plates, electrotype plates and other metallic printing plates which comprises etching an image on 105 the surface of a metallic make-ready sheet

- corresponding with the image on the printing side of a metallic printing plate to be operated upon, but with elevated surface portions of the make-ready sheet in contact with 6 depressed surface portions of the metallic printing plate and depressions in the etched surface of the make-ready sheet in contact with elevated surface portions of the metallic printing plate, then forcing the etched 70 surface of the make-ready sheet against and into the surface of the metallic printing plate thereby impressing upon the printing surface of the metallic printing plate the surface gradations on the opposed surface of the 75 etched metallic make-ready sheet.
5. A process of treating half-tone plates, electrotype plates and other metallic printing plates, which comprises coating a metallic make-ready sheet with a coating 80 formed of a sensitized solution adapted to be affected by the action of rays of light, placing over the coated surface of such make-ready sheet an image, and exposing the coated plate and image to the action of rays of light while the image is between the coated surface and the source of light, then developing and etching the image in the metallic surface of the make-ready sheet, and then bending and correcting the printing surface of a metallic printing plate by pressing the etched 85 surface of the metallic make-ready sheet in contact and bending engagement with said printing surface.
6. A process of treating half-tone plates, electrotype plates and other metallic printing plates, which comprises coating a metallic make-ready sheet with a coating 90 formed of a sensitized solution adapted to be affected by the action of rays of light, placing over the coated surface of such make-ready sheet an image and exposing the coated plate and image to the action of rays of light while the image is between the coated surface and the source of light, then developing and etching the image in the metallic surface of the make-ready sheet, then laying the etched 95 surface of the make-ready sheet in contact with the printing side of a metallic printing plate to be operated upon, then forcing the etched surface of the metallic make-ready sheet against the printing surface of the metallic printing plate, thereby impressing upon the printing surface of the metallic printing plate the impression of the etched surface of the make-ready sheet.
7. A process of treating half-tone plates, electrotype plates and other metallic printing plates, which comprises coating a metallic make-ready sheet with a coating formed 100 of a sensitized solution adapted to be affected by the action of rays of light, placing upon the coated surface of such make-ready sheet an image in ink and exposing the coated sheet and image to the action of rays of light, then developing the coated make-ready sheet by subjecting it to the action of acid, then placing the etched side of the make-ready sheet in contact with the printing side of a metallic printing plate to be operated upon, and then forcing the etched surface of the metallic make-ready sheet against the printing surface of the metallic printing plate, thereby impressing upon said printing surface the impression of the etched surface of said make-ready sheet.
8. A process of treating half-tone plates, electrotype plates, and other metallic printing plates, which comprises coating a metallic make-ready sheet with a coating of sensitized material adapted to be affected by the action of rays of light, placing upon the coated surface of the make-ready sheet an image in ink, exposing the coated sheet and image to the action of rays of light, then developing the coated make-ready sheet by subjecting it to the action of water, thereby 105 removing relatively soft ink-protected portions of the sensitized coating from the metallic surface leaving portions of said metallic surface exposed, and leaving other portions of the sheet covered with said coating material, then allowing the plate to dry, then etching said make-ready sheet by subjecting it to the action of acid, then placing the etched side of the make-ready sheet in contact with the printing side of a metallic printing plate to be operated upon, and then forcing the etched surface of the metallic make-ready sheet against the printing surface of the metallic printing plate, thereby impressing upon said printing surface the impression of the etched surface of said make-ready sheet.
9. A process of treating half-tone plates, electrotype plates or other metallic printing plates, which comprises coating a metallic make-ready sheet with a coating of sensitized material adapted to be affected by the action of rays of light, placing upon the coated surface of the make-ready sheet an image in ink taken from the printing surface of a printing plate, exposing the coated sheet and image to the action of rays of light, then developing the coated make-ready sheet by subjecting it to the action of water, thereby removing relatively soft ink-protected portions of the sensitized coating from the metallic surface, and leaving other portions of the sheet covered with said coating material, then allowing the sheet to dry, then etching said make-ready sheet by subjecting it to the action of acid, then 110
10. A process of treating half-tone plates, electrotype plates and other metallic printing plates, which comprises coating a metallic make-ready sheet with a coating of sensitized material adapted to be affected by the action of rays of light, placing upon the coated surface of the make-ready sheet an image in ink taken from the printing surface of a printing plate, exposing the coated sheet and image to the action of rays of light, then developing the coated make-ready sheet by subjecting it to the action of water, thereby removing relatively soft ink-protected portions of the sensitized coating from the metallic surface, and leaving other portions of the sheet covered with said coating material, then allowing the sheet to dry, then etching said make-ready sheet by subjecting it to the action of acid, then 115
11. A process of treating half-tone plates, electrotype plates and other metallic printing plates, which comprises coating a metallic make-ready sheet with a coating of sensitized material adapted to be affected by the action of rays of light, placing upon the coated surface of the make-ready sheet an image in ink taken from the printing surface of a printing plate, exposing the coated sheet and image to the action of rays of light, then developing the coated make-ready sheet by subjecting it to the action of water, thereby removing relatively soft ink-protected portions of the sensitized coating from the metallic surface, and leaving other portions of the sheet covered with said coating material, then allowing the sheet to dry, then etching said make-ready sheet by subjecting it to the action of acid, then 120
12. A process of treating half-tone plates, electrotype plates and other metallic printing plates, which comprises coating a metallic make-ready sheet with a coating of sensitized material adapted to be affected by the action of rays of light, placing upon the coated surface of the make-ready sheet an image in ink taken from the printing surface of a printing plate, exposing the coated sheet and image to the action of rays of light, then developing the coated make-ready sheet by subjecting it to the action of water, thereby removing relatively soft ink-protected portions of the sensitized coating from the metallic surface, and leaving other portions of the sheet covered with said coating material, then allowing the sheet to dry, then etching said make-ready sheet by subjecting it to the action of acid, then 125
13. A process of treating half-tone plates, electrotype plates and other metallic printing plates, which comprises coating a metallic make-ready sheet with a coating of sensitized material adapted to be affected by the action of rays of light, placing upon the coated surface of the make-ready sheet an image in ink taken from the printing surface of a printing plate, exposing the coated sheet and image to the action of rays of light, then developing the coated make-ready sheet by subjecting it to the action of water, thereby removing relatively soft ink-protected portions of the sensitized coating from the metallic surface, and leaving other portions of the sheet covered with said coating material, then allowing the sheet to dry, then etching said make-ready sheet by subjecting it to the action of acid, then 130

forcing the etched surface of the make ready sheet against the printing surface of the metallic printing plate, thereby impressing upon the printing surface of the latter the impression of the etched surface of said make-ready sheet.

10. A process of treating half-tone plates, electrotype plates, and other metallic printing plates, which comprises coating a metallic make-ready sheet with a coating of sensitized material adapted to be affected by the action of rays of light, placing upon the coated surface of the make-ready sheet a transparent sheet containing an image 15 formed of material which is light-resisting exposing the coated sheet and image to the action of rays of light, then developing the coated make-ready sheet by subjecting it to the action of water, thereby removing relatively soft portions of the sensitized coating 20 from the metallic surface, and leaving other portions of the make-ready sheet covered with said coating material, then allowing the plate to dry, then etching said make-ready sheet, then forcing the etched surface of the make-ready sheet against the printing surface of a metallic printing plate to be operated upon, thereby impressing upon said printing surface the impression 25 of the etched surface of said make-ready sheet.

11. A process of treating half-tone plates, electrotype plates, and other metallic printing plates, which comprises coating a metallic make-ready sheet with a coating of sensitized material adapted to be affected by the action of rays of light, placing upon the coated surface of the make-ready sheet an image formed of light-resisting material, 35 exposing the coated sheet and image to the action of rays of light, then applying a layer of acid-resisting material to the surface of the sensitized coating on the make-ready sheet, then developing the coated make-ready sheet by subjecting it to the action of water, thereby removing relatively soft portions of the sensitized coating from the metallic surface, and leaving portions of the make-ready sheet covered with said coating 40 material, then allowing the sheet to dry, then etching said make-ready sheet by subjecting it to the action of an acid, and then forcing the etched surface of the make-ready sheet against the printing surface of a metallic printing plate to be operated upon, thereby impressing upon said printing surface the impression 45 of the etched surface of said make-ready sheet.

12. A process of treating half-tone plates, 50 electrotype plates or other metallic printing plates, which comprises coating a metallic make-ready sheet with a coating of sensitized material adapted to be affected by the action of rays of light, placing upon the 55 coated surface of the make-ready sheet an

image formed of light-resisting material, such, for example, as ink, exposing the coated sheet and image to the action of rays of light, then applying a layer of acid-resisting material to the surface of the sensitized coating on the make-ready sheet, then developing the coated make-ready sheet by subjecting it to the action of water, thereby removing relatively soft portions of the sensitized coating from the metallic surface of the sheet and leaving other portions of the make-ready sheet covered with said coating material, then allowing the plate to dry, then applying powdered material, such for example as dragon's blood powder to the surface of the plate, then heating the plate and the coating material and powdered material on the plate, then etching the make-ready sheet by subjecting it to the action of acid, then placing the etched side of the make-ready sheet in contact with the printing side of a metallic printing plate to be operated upon, and then forcing the etched surface of the metallic make-ready sheet against the printing surface of the metallic printing plate.

13. A process of treating half-tone plates, electrotype plates or other metallic printing plates, which comprises coating a metallic make-ready sheet with a coating of sensitized material adapted to be affected by the action of rays of light, placing upon the coated surface of the make-ready sheet an image in ink from the printing surface of a printing plate, exposing the coated sheet and image to the action of rays of light, then applying a layer of acid-resisting material to the surface of the sensitized coating on the make-ready sheet, then developing the coated make-ready sheet by subjecting it to the action of water, thereby removing relatively soft portions of the sensitized coating from the metallic surface of the sheet and leaving other portions of said sheet covered with coating material, then allowing the plate to dry, then applying powdered resinous material such as dragon's blood powder to the surface of the plate, then heating the plate to melt and harden the powdered material to form an acid-resisting coating, then etching the sheet by subjecting it to the action of acid, and then forcing the etched surface of the make-ready sheet against the printing surface of the metallic printing plate, thereby impressing upon said printing surface the impression of the etched surface of said make-ready sheet.

14. A process of treating half-tone plates, electrotype plates, or other metallic printing plates which comprises coating a metallic make-ready sheet with a coating of sensitized material adapted to be affected by the action of rays of light, placing upon the coated surface of the make-ready sheet an

- image in ink taken from the printing surface of a printing plate, such, for example, as a photo-engraving, exposing the coated sheet and image to the action of rays of light, then applying a coating of ink to the surface of the sensitized coating on the make-ready sheet, then developing the coated make-ready sheet in water, thereby removing portions of the sensitized coating 5 from the metallic surface of the sheet and leaving portions of said sheet covered with coating material, then allowing the plate to dry, then applying powdered resinous material such as dragon's blood powder to the 10 surface of the plate, then heating the plate to melt and harden the powdered material to form an acid-resisting coating, then etching the coated sheet by subjecting it to the action of a solution containing nitric acid, 15 thus forming the high-light surfaces in the form of depressions in the make-ready plate, and middle-tone surfaces in the form of less depressed surface portions of said plate, and said middle-tone surfaces and the relatively 20 high shadow tone surfaces being left partially covered by acid-resisting material and by sensitized coating material, then removing all of the ink from the surface of the sensitized coating material and plate, then 25 removing the sensitized coating material from the middle-tone surfaces by applying thereto a solution containing muriatic acid, thereby leaving the high-light surfaces and middle-tone surfaces of the metallic sheet 30 exposed and in condition to be acted upon by acid, then subjecting the plate to the action of a solution containing nitric acid thereby lowering the high-light and middle-tone surfaces with respect to the shadow-tone surfaces on which acid resisting material still remains, then washing the plate with water, and again subjecting it to the action of a solution containing muriatic acid, thereby removing all of the remaining 35 sensitized solution, then again washing the sheet with water and again subjecting it to the action of a solution containing nitric acid to reduce the sharpness of the angles, then removing the acid resisting material 40 covering the back of the make-ready sheet, and the nitric acid solution from the surface of the sheet, then forcing the etched surface of the metallic make-ready sheet against the printing surface of the metallic printing plate thereby impressing upon said printing surface the impression of the etched surface 45 of said make-ready sheet.
15. A process of making make-ready sheets for use in treating half-tone plates, 50 electrototype plates or other metallic printing plates, which comprises coating the metallic sheet with a coating of sensitized material which is adapted to be affected by the action of rays of light, then etching the coated sheet by subjecting it to the action of a so- 55 lution containing nitric acid, thus forming high-light surfaces, and middle tone surfaces, but leaving shadow tone surfaces partially covered with acid-resisting material 60 and by sensitized coating material, then removing all of the ink from the surface of the sensitized coating material and plate, then removing the sensitized coating material from the middle-tone surfaces by applying thereto a solution containing muriatic acid, thereby leaving the high-light surfaces and middle-tone surfaces of the metallic sheet exposed and in condition to 65 be acted upon by acid, then subjecting the plate to the action of a solution containing nitric acid, thereby lowering the high-light and middle tone surfaces with respect to the shadow-tone surfaces on which acid-resisting material is still allowed to remain, then 70 washing the plate with water, then again subjecting it to the action of a solution containing muriatic acid, thereby removing all of the remaining sensitized solution, then 75 washing the sheet with water and again subjecting it to the action of a solution containing nitric acid to round off the angles, then wash off the nitric acid solution, and then removing the acid-resisting material 80 covering the back of the sheet.
16. A process of treating half-tone plates, electrototype plates and other metallic printing plates, which comprises coating a metallic make-ready sheet with a coating formed of a sensitized solution adapted to be affected by the action of rays of light, placing in juxtaposition to the coated surface of such make-ready sheet an image in ink and exposing the coated plate and image to the action of rays of light, then developing and 85 etching the image in the metallic surface of the make-ready sheet, said image corresponding with an image on the printing side of a metallic printing plate to be operated upon, but having the high-light surfaces of the etched metallic make-ready sheet in positions corresponding with the shadow-tone surfaces of the metallic printing plate, and having the shadow-tone surfaces of the make-ready plate in positions 90 corresponding with the high-light surfaces of the metallic printing plate, and then forcing the etched surface of the metallic make-ready sheet against the printing surface of the metallic printing plate, thereby impressing upon the high-light surfaces of the printing plate the impression of the opposed surface portions of the etched side of the metallic make-ready plate.
17. A process of treating half-tone plates, electrototype plates and other metallic printing plates, which comprises coating a metallic make-ready sheet with a coating formed of a sensitized solution adapted to be affected by the action of rays of light, placing 95 over the coated surface of such make-ready 100 sheet.

sheet a transparent sheet containing an image and exposing the coated plate and image to the action of rays of light while the image is between the coated surface and the source of light, then developing and etching the image in the metallic surface of the make-ready sheet, then laying the etched surface of the make-ready sheet in contact with the printing side of a metallic printing plate to be operated upon, then forcing the etched surface of the metallic make-ready sheet against the printing surface of the metallic printing plate, thereby impressing upon the printing surface of the metallic printing plate the impression of the etched surface of the make-ready sheet.

18. A process of treating half-tone plates, electrotype plates, and other metallic printing plates, which comprises coating a metallic make-ready sheet with a coating of sensitized material adapted to be affected by

the action of rays of light, placing upon the coated surface of the make-ready sheet a printed sheet containing an image in ink, exposing the coated sheet and image to the action of rays of light, then developing the coated make-ready sheet, then etching said make-ready sheet by subjecting it to the action of acid, then laying the etched surface of the make-ready sheet in contact with the printing side of a metallic printing plate to be operated upon, then forcing the etched surface of the metallic make-ready sheet against the printing surface of the metallic printing plate, thereby impressing upon the printing surface of the metallic printing plate the impression of the etched surface of the make-ready sheet.

Signed at Chicago, in the county of Cook and State of Illinois this 22nd day of July, 1922.

JULIUS DICKERT.
